(57) **CLAIM**

The ornamental design for a notebook computer, as shown and described.

DESCRIPTION

FIG. 1 is a perspective view of a notebook computer showing our new design;
FIG. 2 is a front view thereof;
FIG. 3 is a rear view thereof;
FIG. 4 is a left side view thereof;
FIG. 5 is a right side view thereof;
FIG. 6 is a top plan view thereof;
FIG. 7 is a bottom plan view thereof;
FIG. 8 is a perspective view illustrating a closed state thereof;
FIG. 9 is a perspective view thereof showing the state that the side docking hinge has been slid and exposed;
FIG. 10 is a front view of FIG. 9;
FIG. 11 is a rear view of FIG. 9;
FIG. 12 is a top plan view of FIG. 9;
FIG. 13 is a bottom plan view of FIG. 9; and,
FIG. 14 is a perspective view of FIG. 9 in a condition that a mobile phone has been docked.
The broken lines show unclaimed subject matter only and form no part of the claimed design. The dash-dot broken lines define the bounds of the claimed design and form no part thereof.
